STOKER

George Ross McGee, Sarnia Township, Ontario,
Canada

Application February 19, 1937, Serial No. 126,560

1 Claim. (Cl. 110—45)

My invention relates to underfeed stokers for boilers, furnaces and the like.

The objects of the invention, generally, are to improve on known stokers.

5 A specific object of the invention is to provide means for automatically and periodically agitating the lower stratum or layer of coal in the hopper, whereby the coal is agitated or loosened and easily feeds by gravity into the charging duct leading to the retort or fire box of the furnace.

10 Another specific object is to provide an adjustable door over the agitator or bottom of the feed or fuel hopper, whereby the quantity of fuel falling into the charging duct is regulated.

15 Another specific object is to provide a closed or sealed hopper having means adapted to allow any gas or fumes backing into the hopper to be released to the atmosphere.

20 Another specific object is to provide a reciprocating feeding ram which may be actuated by a fluid, such as water or oil, for instance.

25 Another specific object is to provide a scraper or member which is actuated by the ram, the free end of the scraper riding upon the wall of the fire box whereby the fuel bed is agitated.

Still another object is to provide a fire box having superposed rings formed to provide tuyères.

30 In the drawings, wherein like numerals of reference indicate corresponding parts in the various figures,

Figure 1 is a fragmentary, longitudinal section of a stoker constructed in accordance with this invention;

35 Figure 2 is a fragmentary plan view of Figure 1;

Figure 3 is a cross sectional view; and,

Figure 4 is a longitudinal section of the fluid pumping unit.

40 Fig. 5 is a fragmentary side elevation view of a stoker showing certain details.

Fig. 6 is a fragmentary plan view of Fig. 5.

Referring now by numerals to the drawings, B indicates the fire box of a fuel burning plant, 45 such as a furnace for instance. The fire box may comprise a base member 11, substantially cup-shaped, having a circular extension 12 projecting outwardly. The base is formed with a flat peripheral flange 13 upon which rest a plurality of 50 superposed rings 14 formed on one face with radially directed passages or air jets 15. The inner faces or edges of the rings may be slanted to extend or continue the general inner contour of the base. Spaced from the outer edges of the 55 rings is a sleeve or ring 16 encircling a ring, or

segments of a ring, 17, which in turn encircle, but 5 is or are spaced from, the outer edges of the rings 14, to provide an air space 18 communicating with the air jets 15. The ring 17 is formed at the top with a rounded inwardly-directed flange 20 extending to about the inner edge of the uppermost ring 14. Apertures 18A through the flange 13 of the base permit air to pass into the compartment 18, to be distributed through the retort.

10 H is the fuel hopper, having the slanting bottom wall 21, top wall 22, forward wall 23 and box-like forward portion 24. In the bottom wall 21, and within the box-like portion 24, is a discharge opening 25. The top wall 22 is formed 15 with a charging opening which is closed by a suitable removable lid 26; the box-like portion 24 is preferably provided with an opening which is closed by a suitable lid 27. The lids should preferably be so constructed that the hopper is substantially sealed to prevent escape of gases or fumes which may find their way into the hopper. Suspended adjacent the forward wall 23, by screws 29 and nuts 30, and extending substantially over the entire width of the hopper, is a door 25 20 25 31. The position of the lower edge of the door with respect to the bottom wall 21 defines the throat or effective opening through which the fuel falls into the bottom of the portion 24.

20 Arranged below the hopper, and between the same and the fire box B, is the fuel charging duct 35, the inner end of the duct engaging into the circular extension 12. The duct, which is preferably circular in cross section, has a flange or connection 36 arranged to lie below the opening 25 35 25 of the hopper, to receive the fuel falling out of the hopper or more particularly the portion 24 thereof.

25 Fixed to the end of the duct 35 farthest from the retort is a casting or head 39 formed with a centrally-located opening to provide a slide bearing for the ram R which must reciprocate within the duct. Suitable packing is preferably used at 40 between the reciprocable ram and the duct head 39.

30 Fitted to the outer end of the ram is a head 44 having a tubular sleeve or extension 45 to which is fitted a cap or closure 46; the cap has a centrally-located opening adapted to slidably receive a pipe or duct 47. The pipe extends 50 between, and is fixed or fitted to a head 39A at one end and to a fixed head or block 49 at the other or outer end.

35 As the head 44 moves with the ram R, suitable packing is preferably provided as at 48, that is, 55

between the tubular sleeve 45 and the pipe 47. As shown, one or more ports 50 are provided through the pipe or tube 47, adjacent the head 39A of the duct 47.

5 Within the tube 47 and fixed at its ends in the head 39A and the fixed block 49, is a tube or pipe 58. The outer end of the tube 58 is operatively connected, as by a pipe 59, to one port of the pump P (to be described later), and the tube 10 47 is operatively connected, as by a pipe 60, to another port of the pump. The pump operates to force a fluid into the inner pipe 58 while withdrawing fluid from the outer pipe 47, and to force the fluid into the outer pipe 47 while withdrawing 15 fluid from the inner pipe 58, alternately. When the fluid is forced into the outer pipe 47, the ram slides in the head 39 away from the fire box, since the fluid will pass through the orifices 50, into the space between the fixed head 39A and the ram head 44, the fluid in the inner pipe 58 and ram R being withdrawn. When, on the other hand, the fluid is forced into the inner pipe 20 58, the ram slides in the fixed head 39 toward the fire box, the fluid between the fixed head 39A and ram head 44 passing through the orifices 50 into the outer tube 47.

To the inner end of the ram is pivotally mounted, as at 68A, a bar or scraper 61, adapted to ride or slide at the free or inner end on the 25 curved wall of the base 11 of the fire box, so as to agitate the fuel bed by the reciprocating movement of the ram R.

30 Preferably, a plate 69 is removably secured to the flange 36 of the fuel duct 35, and formed or curved on its lower edge to just clear a portion of the periphery of the ram, the plate providing a wall closing the duct 35 at the hopper discharge outlet 25.

35 Resting upon the bottom wall 21 of the hopper 40 is a plate or false bottom 65, and between this plate and the crank 70 of a shaft 71, is a connection or link 72, the link passing through the forward wall of the hopper portion 24. The link is pivotally connected at one end to the crank 45 70, as at 73, and pivotally connected at the other end to the plate 65 as by a bolt or the like 78A passing through the curved end 73A of the link. The shaft 71 may be journaled in suitable brackets 75 secured to the forward wall of the hopper portion or extension 24. Fixed to one end of the 50 shaft 71, adjacent one of the brackets 75, is a lever 76 which is directed downwardly to engage in a recess 77 formed in the horizontal leg of an angle member 78. The horizontal leg of the 55 angle 78 slides on a bar 79 spaced from and arranged parallelly with one of a pair of channels 80, while the vertical leg of the angle 78 slides between the bar 79 and the channel, all as best shown in Figure 3. One end of the angle 78 is 60 secured to the plunger head 44, so that the false bottom 65 of the hopper is actuated back and forth in the hopper by the back and forth movement of the plunger or ram R. The angle 78 may be connected to the plunger head 44 as by 65 a member 141 secured at one end to the angle and secured at the other end to the head 44 as by say, a pin or the like 142. To provide a clearance for the member 141, the adjacent channel 80 may be notched as at 140.

70 Air is forced into the base of the retort, from a suitable fan F, through an air duct (or ducts) D opening into the base below the flange 13. The fan may be used to operate the oil pump P actuating the ram R, the fan shaft S having fixed 75 thereon a driving pulley P1.

While the invention is not limited to the use of a fluid pump for operating the ram, there is shown a satisfactory pump or oil feeding system. There is used a reservoir or casing 85 in the bottom of which is stored a suitable volume of oil. 5 Associated with the reservoir, and preferably within the same, is the pump P, (of the plunger type), having a cylinder 86 in which slides a piston 88 actuated or reciprocated by a piston rod 89 eccentrically mounted on a suitably journaled shaft 90. Fixed to one end of the shaft 90 is a pulley 91. Between the driving pulley P1 on the fan shaft, and the pulley 91, is tensioned a belt 93, so that the plunger or piston 88 of the oil feeding system is actuated by the fan F. The relative diameters of the pulleys P1 and 91 are such that the rotary speed of the latter is considerably reduced. Operatively connected with the inside of the cylinder 86, rearwardly of the piston 88, are two ports 95 and 96; from the port 95 extends a pipe 97 the open end of which is immersed in the body of oil in the casing 85, while a pipe 98 extends from the port 96 into a valve casing 99. Within the port 96 is a ball valve 100, the ball resting upon shoulders formed by locally restricting the diameter of this port, so that the ball will operate to stop the flow of oil in one direction, while it will permit of a flow of oil in the opposite direction. Thus, when the piston is advanced toward the ports, oil will be forced into the valve casing 99, while during the opposite travel of the piston, the ball will operate to prevent oil from being sucked into the cylinder from the valve casing. Supported in a restricted portion of the other port, 95, is a similar ball valve 101. As the piston travels away from the ports, oil will be sucked into the cylinder from the bottom of the casing, while on an opposite travel of the piston, the oil in the cylinder is prevented from being forced back into the casing and is forced into the valve casing. From two spaced ports 102 and 103 extend the two pipes 55 and 60 aforesaid, respectively, so that the inside of the valve casing is operatively connected with the aforesaid pipes 58 and 47, respectively. 45

50 Within the valve casing 99 is a loosely mounted valve unit comprising four discs, 105, 106, 107, and 108, rigidly mounted on a rod 109, the rod extending beyond both opposite discs 105 and 108. Arranged, preferably above the bore or longitudinal axis of the valve casing 99, is an open end cylinder 110, which is operatively connected to the inside or bore of the valve casing 99 by three spaced ports or passages 111, 112 and 113; the opposite passages 111 and 113 open into or 55 communicate with the opposite ends of the valve casing, while the centre or intermediate port 112 opens into the centre of the casing 99. Slidable in the cylinder 110 are two spaced discs or pistons 116 and 117 fixed to an operating rod 115 which is operatively connected at one end to the ram head 44, so that the discs or valves 116 and 117 are actuated within the cylinder 110 by the movement of the ram R. The operative connection between rod 115 and head 44 may comprise a 60 horizontally arranged block 125 slotted at 126 to receive a roller 127 turning on the free end of the rod. The discs 116 and 117 are so disposed on the rod 115 that the space or compartment defined by the wall of the cylinder and the two 65 discs is in operative communication with both of the ports 112 and 113, or with both ports 111 and 112, alternately. When in operative communication with both ports 112 and 113, (see Figure 4), and the piston 88 of the pump is mov- 70 75 80 85 90 95 100 105 110 115 120 125 130

ing towards the ports 96 and 95, oil from the pump cylinder passing through the ports 112 and 113, will cause the four discs, 105-108, to move to the position shown in Figure 4, forcing a stream of oil into the feed pipe or line 59 and into the pipe 58. The ram R will now be travelling toward the retort, the oil in the pipe 47 passing through the pipe 60, to enter the casing 99 through the port 103 and to discharge into the reservoir through the port 103A. When the discs 116 and 117 have been actuated to a position shown in dotted lines in Figure 4, the four discs, 105 to 108, will move to a position opposite that shown in full lines in Figure 4, and oil will be forced out of the casing 99 through the port 103, into the pipe 60 and into the pipe or tube 47, to move the ram R away from the retort, the oil in the pipe 58 passing through the pipe 59 to enter the valve casing 99 through the port 102 and be discharged into the reservoir through the port 102A.

The hopper may be operatively connected to a chimney, as by a pipe (not shown) connected at one end to an opening 24A, so that any fumes in the hopper will be withdrawn.

Operation

The motor-operated fan which is controlled by a thermostat (not shown) operates to force the required draft to the retort. While the fan is operating, the fluid or oil pump is operated to force oil into the pipes 47 and 58, alternately, actuating the ram R toward, or away from, the retort, alternately. The movement of the ram toward the retort operates to feed a certain volume of fuel or coal into the bottom of the retort. The movement of the ram operates to slide the false bottom or plate 65 on the bottom wall 21 of the retort to thus further agitate the contents of the hopper. The length of the recess 77 in the angle 78 is such as to provide lost motion

in the lever 78, that is, the lower end of the lever will be moved a relatively small distance. The movement of the ram will also actuate the operating link 115 of the pump. In order that the rod 115 may be moved a small distance relatively to that of the ram, the block 125 is accordingly slotted at 126 to a comparatively long distance. If smoke, for any reason, is drawn into the feed duct 35 by the outward stroke of the ram R, then the smoke will find its way into the hopper, from which it will be exhausted through the vent opening 24A. It will be clearly seen that as the bottom of the hopper is inclined, the false bottom 65 upon sliding back and forth will elevate and lower the connecting rod 72 bodily, at least at 15 the end thereof which is connected to the false bottom, and as the rod is substantially all enclosed within the hopper, the action of the rod will be to further agitate the hopper contents.

What I claim is:

In an underfeed stoker, the combination of a retort, a fuel hopper having a bottom inclined downwardly toward said retort, and a vertical wall on its side which is adjacent to said retort, said bottom having a discharge opening adjacent 25 the lower end thereof, an agitating member slidably mounted above said bottom, a duct operatively connected between said opening and said retort, a ram in said duct for feeding fuel into said retort, means for actuating said ram, a lever 30 pivotally mounted adjacent said wall to oscillate in a vertical plane toward and away from said hopper, means operatively connecting said lever to said ram to oscillate said lever, and a connection pivotally connected between said lever and 35 said agitator, said connection passing through said wall and lying substantially entirely within said hopper whereby the movement of said connection in a vertical plane operates to agitate the fuel in said hopper.
